UNITED STATES PATENT OFFICE

2,307,636

HEAT RESPONSIVE DEVICE

Robert E. Newell, Irwin, Pa., assignor to Robert-shaw Thermostat Company, Youngwood, Pa., a corporation of Pennsylvania

Application August 3, 1940, Serial No. 350,926

3 Claims. (Cl. 236—15)

This invention relates to heat responsive devices, and more particularly to such devices for controlling valves, switches and the like thermostatically.

In devices of this character using an expandible and contractible power element as part of the thermostatic control it is often desirable to arrange this element in opposed relationship with the member which it actuates. For example, the expansive movement of the power element may be used to force valve or switch members to a closed position instead of merely relieving pressure on these members and permitting springs or other yieldable devices to close them. However, in such arrangements the temperature at which the power element is designed to close the valve or switch may be exceeded, causing additional expansion of the element and consequent damage to the parts.

The present invention will be described in connection with a thermostatic valve used in connection with a domestic gas range but it is to be understood that it is not limited to the use of a valve as the controlling member and it also may be applied to the control of other types of heating apparatus.

It is an object of the invention to prevent damage to the valve and other parts when the temperature at which the valve is set to close is exceeded.

Another object of the invention is to permit dismantling of the valve and associated parts as a unit for cleaning and repair so that replacement is facilitated.

Other objects and advantages will become apparent from the following description taken in connection with the accompanying drawing which is a front elevation partly in section of a thermostatic valve embodying the invention.

Referring more particularly to the drawing, the thermostatic valve includes a main casing 10 provided with an inlet 12 for gas or other fluid and having an end casing 14 detachably secured thereto as by means of the screws 16. The end casing 14 is provided with an outlet 18 for the gas or other fluid which flows from the inlet 12 through both casings. At the opposite end of the main casing 10 is a spud piece 20 forming a support for an operating shaft 22 carrying the usual dial 24.

The thermostatic valve thus far described is designed to be housed behind the front panel 26 of a domestic gas range, with the dial 24 and part of the spud piece 20 projecting through the front panel for convenient operation. The thermal

control assembly for the device in this arrangement comprises a bulb 28, which is located in the oven of the range, and tube 30 operatively connected to an expandible and contractible power element 32 housed within the end casing 14. In this instance, the end of the tube 30 adjacent the power element 32 is secured in sealing engagement with a stud 34 which projects from the end casing 14 and is secured thereto by means of the nut 36. The inner end of stud 34 abuts the power element 32 and is provided with an aperture 38 affording communication between the tube 30 and the interior of the power element. This thermal control assembly comprising the bulb 28, tube 30 and power element 32 are filled with a liquid which upon changes in temperature sensed by the bulb 28 will serve to expand and contact the power element 32 as is well known to those skilled in the art.

The operating shaft 22 is suitably bored to receive the end of a valve shaft 40 which is adapted for longitudinal movement therein, being prevented from relative rotation by means of a driving pin 42 projecting therefrom into engagement with a slot 44 formed at the end of the operating shaft 22. The valve shaft 40 is provided, intermediate its ends, with an enlarged portion 46 having a ball face formed on one side thereof. The end 48 of the valve shaft 40 which projects beyond the enlargement 46 is reduced in diameter and has a threaded thimble 50 secured on the end thereof. It will be understood that the thimble 50 may be dispensed with if desired and the threads be formed directly on the reduced end 48. The shoulder formed by the junction of the enlarged portion 46 with the valve shaft 40 is designed to afford an abutment for one end of a coil spring 52, the other end of which may abut a portion of the casing 10.

Communication through the casing between the inlet opening 12 and outlet 18 is controlled by a valve member 54 which is loosely mounted on reduced end 48 of valve shaft 40 and is adapted to engage a valve seat 56 formed on the casing 10. The engagement of valve member 54 with the valve shaft 40 is effected by the provision of a ball seat 58 on the valve member 54 which seat is preferably ground and lapped into sealing engagement with the ball face of enlargement 46. This arrangement permits the valve member to move bodily and also tilt on the shaft 40 without danger of leakage between these parts.

From the details of construction so far described, it will be apparent that movement of the power element 32 when undergoing expan-

sion is toward the left as viewed in the drawing and that seating movement of valve 54 is also in this direction. Hence, the valve member 54 and the power element 32 work in opposition to each other, due to the fact that the expansive movement of the power element 32 is in a direction tending to force the valve member 54 toward the valve seat 56. This invention is particularly directed toward provision of means for actuating the valve member thermostatically under these conditions without damage thereto or to the associated parts.

To this end, the valve member 54 is provided on the side opposite the ball seat 58 with a nose portion 60 forming an abutment for a cup-shaped washer 62 loosely mounted on the projecting end 48 of the valve shaft 40. One end of coil spring 64 is housed within the washer 62 and the other end projects into the enlarged end 65 of a cap member 66. The cap member 66 is adapted to telescope on a collar 72 having threaded engagement with the thimble 50. The spring 64 serves to force the end of the cap member 66 into constant engagement with the power element 32. Diametrically opposite slots 68 are provided in the cap member 66 and adapted to receive in sliding engagement a pin 70 projecting from the collar 72.

Rotation of the collar 72 with the thimble 50 is prevented by the extension of the pin 70 into suitable diametrically opposite slots 74 formed in a guide member 76 surrounding the cap member 66. The guide member 76 is provided with oppositely disposed flanges 78 which engage in suitable slots 80 formed in the end casing 14 and serve to anchor this member 76 against movement therein. Preferably, the ends of the flanges 78 which engage in the slots 80 are reversely bent or otherwise affixed in the end casing 14 to afford secure connection of the guide member 76 therein.

In the operation of the device, the dial 24 is rotated to any desired setting, which rotation will serve to move the thimble 50 of the valve shaft 40 longitudinally into the collar 72 and thus cause movement of the valve member 54 away from its seat. This manual adjustment of the device permits gas to flow from the inlet 12 past the valve and through the outlet 18 to the point of use, such as the oven of a domestic gas range. When the temperature of the oven as sensed by the bulb 28 reaches that for which the dial has been set, the power element 32 will expand, forcing the cap member 66 to the left, as viewed in the drawing. Due to the fact that the spring 64 is stronger than the spring 52, the latter will be compressed as the valve moves towards its seat under this thermostatic control. Consequently, the spring 64 will retain the cap 66 in the same relationship with pin 70 as it occupied before the expansive movement of the power element 32 occurred.

It often happens, however, that after the valve is seated, further expansion of the power element 32 occurs. Such movement may be due to the fact that the stove manufacturer has not located the bulb element 28 in the zone of greatest heat in the oven. Consequently, when the portion of the oven in which the bulb is located reaches the temperature for which the dial is set and the power element moves the valve to its seat, there may then be additional heat applied to the bulb as the heat flows thereto from the hotter portion of the oven. This occurrence is known as "overshooting" and is commonly encountered in the use of devices of this character.

When "overshooting" occurs in the use of this thermostatic valve the additional movement of the power element 32 cannot cause damage to the valve member 54 or associated parts. When such movement occurs, the power element 32 merely urges the cap member 66 to the left as viewed in the drawing, causing compression of the spring 64. Such compression will occur whenever the valve member is seated as will be apparent. As soon as the additional heat causing "overshooting" is dissipated the parts will resume normal relationship and the setting of the thermostat is not impaired.

Another advantage of the construction of the device is that the end casing 14 can be removed from the main casing 10, together with the valve stem 40 and all the associated parts as a unit, in order that these parts may be cleaned or repaired. It will be observed that upon removal of the screws 16 there is no obstruction to the detachment of the end casing 14 from the main casing 10. Also, due to this construction, the relationship of the parts is not disturbed when the end casing is again assembled, thus facilitating assembly of the control.

I claim:

1. In a thermostatic structure for controlling the temperature of an oven and the like, a stationary element, a movable element engageable with said stationary element, thermally responsive means for adjusting said movable element with respect to said stationary element to maintain selected temperatures, a manually actuatable shaft engaging said movable element, a projection on said shaft extending beyond said movable element and terminating short of the thermally responsive means, adjustment means having threaded engagement with said projection for positioning said movable element with respect to said stationary element to select different temperatures to be maintained by said thermally responsive means, means to anchor said adjustment means against rotation, a cap member abutting said thermally responsive means and telescopically mounted on said adjustment means, means on said cap cooperating with said anchor means to limit said telescopic movement, and a coil spring supported on said adjustment means between said movable element and cap for absorbing movements of the thermally responsive means due to additional heat being applied thereto after the elements are engaged.

2. In a thermostatic structure for controlling the temperature of an oven and the like, a main casing, an end casing detachably mounted on said main casing, a valve seat in said main casing, and a thermostatic valve assembly cooperating with said seat to maintain selected temperatures in the oven, said assembly comprising a valve member engageable with said valve seat, a valve shaft supported for rotation in said main casing and projecting through said valve member, thermally responsive means supported in said end casing and spaced from the projecting end of said shaft, adjustment means having threaded engagement with said projecting end for positioning said valve member with respect to said seat, a guide member anchored in said end casing and extending around said adjustment means, an abutment member for said thermally responsive means and slidably mounted between said adjustment means and guide member, a limit stop projecting from said adjustment means through said abutment and guide members for restraining relative rotation and for limiting slidable movement between said

adjustment means and abutment member, and a yieldable member extending from said abutment member to said valve member for absorbing movements of the thermally responsive means after said valve member is engaged with its seat, said valve assembly being removable as a unit from the main casing when the end casing is detached therefrom.

3. In a thermostatic structure for controlling the temperature of an oven and the like, a stationary element, a movable element engageable with said stationary element for controlling the supply of fuel to said oven, thermally responsive means for operating said movable element into engagement with said stationary element, manually actuatable means for operating said movable element in opposition to said thermally responsive means, said manually actuatable means having a portion projecting through said movable element and spaced therefrom to permit relative

angular movement, sealing means effective between said movable element and manually actuatable means for preventing leakage of fuel through said space when said elements are engaged, adjustment means carried by said projection for positioning said movable element with respect to said stationary element upon operation of said manually actuatable means, and yieldable means extending from said movable element to said thermally responsive means for transmitting movements of the latter to said movable element and for absorbing movements of said thermally responsive means after said elements are engaged, said yieldable means being operable by said thermally responsive means independent of said adjustment means and projection when said elements are engaged whereby said sealing means remains effective during said movements.

ROBERT E. NEWELL.
